PARALLEL COMPRESSION TAP

John J. Klosin, New Brunswick, N. J., assignor to The Thomas & Betts Co., Elizabeth, N. J., a corporation of New Jersey

Application December 2, 1957, Serial No. 48,733

Term of patent 14 years

(Cl. D26—1)

Fig. 1.

Fig. 2.

Fig. 1 is a view in perspective of the parallel compression tap showing my new design; and

Fig. 2 is a view in side elevation, partly in section, of the parallel compression tap design shown in Fig. 1.

The opposite sides and end faces of the parallel compression tap not shown are substantially mirror images of those shown.

I claim:

The ornamental design for a parallel compression tap, as shown and described.
